UNITED STATES PATENT OFFICE.

CLYDE S. MORSE, OF DE KALB, ILLINOIS.

AUTOMATIC SASH LOCK AND HOLDER.

1,186,596.

Specification of Letters Patent. Patented June 13, 1916.

Application filed January 5, 1916. Serial No. 70,374.

To all whom it may concern:

Be it known that I, CLYDE S. MORSE, a citizen of the United States, and resident of De Kalb, in the county of Dekalb and State of Illinois, have invented certain new and useful Improvements in Automatic Sash Locks and Holders, of which the following is a specification.

This invention relates to improvements in a sash-lock, holder or fastener, of a type in which the sash-frame, with which it is designed to coöperate, will be automatically locked or fastened thereby, in a safe, firm and secure manner against vertical movement, and it consists in certain peculiarities of the construction, novel arrangement and operation of the various parts thereof, as will be hereinafter more fully set forth and specifically claimed.

The principal objects of the invention, are, to provide a sash-lock or holder which shall be extremely simple in its construction, automatic in its locking or fastening operation, inexpensive to manufacture, easily applied to a window-casing, almost invisible when in use, and inaccessible to burglars, or from the outside of the window.

Another object is to so construct and arrange the parts of the device that it will co-operate with the window sash in such a manner that the ordinary sash-weights may be dispensed with, if desired, yet so that the sash may be easily raised or lowered and firmly held in any position at which it may be stopped, and so that it will not rattle.

Other objects and advantages of the invention will be disclosed in the subjoined description and explanation.

In the accompanying drawing, which serves to illustrate the invention, Figure 1 is a face view of the lock or holder detached from the window casing and illustrating by continuous lines, the positions the locking levers will occupy when the window-sash is locked thereby, and by dotted lines, the positions to which they may be moved to release the window sash. Fig. 2 is a side view of the holder. Fig. 3 is a view partly in section and partly in elevation, showing the upper part of the holding plate illustrated in Figs. 1 and 2 removed. Fig. 4 is a perspective view of the blank out of which the holding plate is made, illustrating by dotted lines the position to which a part thereof may be turned. Fig. 5 is a front face view showing a modification in the construction

of the holder or lock. Fig. 6 is a side view thereof. Fig 7 is a view in elevation of a portion of one of the jambs or sides of a window frame showing the lock or holder mounted thereon, and Fig. 8 is a side view of like parts.

Like numerals of reference refer to corresponding parts throughout the different views of the drawing.

Referring now to Figs. 1 to 4 inclusive of the drawing, the reference numeral 10 designates the holding or securing plate of the lock, which plate is substantially rectangular in shape as shown, and is provided near one of its edges with openings 11 for the passage of screws used to secure the plate 10 to the window jamb or side of the window frame and within the groove 12 in which the sash 13 operates.

In order that the lock may always be in position to engage and control the movements of the sash, I locate the lock or holder within the groove or channel of the jamb or side of the window frame at a point near the top rail of the lower sash and the bottom rail of the upper sash, when they are in their normal positions, and in order that the holding plate 10 may not interfere with the movement of the sash 13 said plate is countersunk or set in a mortise 14 in the side of the window frame as will be readily understood by reference to Fig. 7 of the drawing. The plate 10 is also provided with openings 15 in which the outer ends 16 of the locking levers 17 are located for pivotal movement. Each of the levers 17 has on its free end an arm 18 which is extended at a right angle or substantially so to its lever 17 as is clearly shown in Figs. 2 and 6 of the drawing. The plate 10 is provided, as shown in Figs. 1 and 4 with a flap 19 which is bent over the pivoted portions of the levers 17 and downwardly between the same as at 19^a in Fig. 4 of the drawing.

The levers 17 and their arms 18 may be made of any suitable size, form and material, but by preference of metal and substantially of the shape shown in Figs. 2 and 3, so that they will be interchangeable, or rather that either one of the levers can be located in either of the openings 15 of the securing plate. The flap or overlying portion 19 may be of such rigidity as to require no rivets to hold it in its overlying position, or it may be riveted in position as shown in Figs. 5 and 6 of the draw-

ing. Located between the levers 17 is a spring 20 which may be of any suitable size, form and material, but in the present instance is shown as being substantially triangular in shape and with its ends overlapping one another at its portion adjacent to the downturned part 19^a of the flap member of the holding plate.

In Figs. 5 and 6 of the drawing I have shown a modification in the construction of the levers which consists in providing each of the same at its pivoted or inner end, with an inwardly turned or deflected portion 21 through each of which, as well as through the flap 19 and plate 10, is extended a pivot pin 22, which not only serve as pivots for the levers 17, but also as rivets for the flap 19. In this modified construction each of the portions 21 is provided with a recess 23 in which the ends of a spring 24 is located, the opposite portion of said spring resting against a pin 25 which secures the flap 19 near its free end to the plate 10. In this modified form the levers 17 are by preference made of flat material instead of wire or rod-like, as shown in the other construction.

From the foregoing, and by reference to the drawing, it will be readily understood and clearly seen, that when the securing or holding plate 10 is positioned in the groove of the jamb or side of the window frame, the arms 18 of the levers will contact at their surface adjacent to the sash with the latter, and said arms will be firmly held in such position by reason of the spring which actuates them from one another. Now, when it is desired to move the sash, for example upwardly, the arms 18 may be pressed toward each other, which operation will release them from the sash and allow it to be freely moved to the desired position, when by releasing the arms, they will again be caused, by reason of the action of the spring, to again engage the sash. It will be understood that it is not necessary to move both of the arms toward each other in order to release the sash, as one of them only may be moved toward the other, when the sash itself will carry the other arm in its movement upward or downwardly. The inner stop 26 of the window frame is provided with a finishing plate 27 to cover up the cut-

out portion of said stop with which the latter is provided, in order to allow the levers 17 and arms 18 to operate therein.

55

Having thus fully described my invention, what I claim as new and desire to secure by Letters Patent, is—

1. In a sash-lock or holder, the combination of a securing plate, with a pair of spring-actuated levers pivotally mounted thereon and each having at its free portion an arm extended therefrom in a horizontal plane to engage the inner surface of a window sash and to furnish handles.

65

2. In a sash-lock or holder, the combination with a securing plate, of a pair of levers pivotally mounted thereon, a spring interposed between said levers to actuate them from each other, an arm on the free end of each lever and extended therefrom in a horizontal plane to engage the inner surface of a window sash and to furnish handles.

70

3. In a sash-lock or holder, the combination with a securing plate having a flap overlying a portion thereof and provided with a deflected portion resting against the face of said plate, of a pair of spring actuated levers pivotally mounted on the plate between the same and said flap and extended outwardly of said deflected portion, an arm on the free end of each lever and extended therefrom in a horizontal plane to engage the inner surface of a window-sash and to furnish handles.

75

4. In a sash-lock or holder, the combination with a securing plate, having an overlying flap provided with a deflected portion resting against the face of said plate, a pair of levers pivotally mounted between the plate and said flap and extended outwardly of the deflected portion thereof, a spring interposed between said flap and plate and between said levers to actuate the latter from each other, an arm on the free end of each lever and extended therefrom in a horizontal plane to engage the inner surface of a window-sash and to furnish handles.
